UNITED STATES PATENT OFFICE

WILLIAM A. N. SPENCER AND WILBERT A. SPENCER, OF LEE, MASSACHUSETTS

PAPER MAKING APPARATUS

Application filed April 5, 1930, Serial No. 441,806. Renewed March 31, 1932.

This invention relates to improvements in paper making apparatus and is directed more particularly to improvements in apparatus for making individual sheets of paper having deckle edges.

It has been the practice to make sheets of paper having deckle edges by hand mold methods, but this has been expensive and therefore objectionable.

It has been attempted in order to overcome this objection to lay separating strips across dandy rolls of paper making apparatus so as to provide separate sheets, but the edges produced were at best no more than imitation deckle edges.

According to this invention we provide apparatus which is adapted for continuous operation and which produces separate sheets each having deckle edges the same as those of hand made paper.

The novel features and advantages of the invention will be observed from the following description thereof which in the form at present preferred is illustrated in the accompanying drawings, in which:

Fig. 1 is a side elevational view of a paper making apparatus embodying the novel features of the invention, with parts in section for clearness.

Fig. 2 is a partial end and sectional elevational view of the apparatus shown in Fig. 1 with parts broken away for clearness, and

Fig. 3 is a partial perspective view of one of the drum platens with certain parts broken away for clearness.

Referring to the drawings the invention will now be described in detail.

In Fig. 1 there is shown a paper making machine with which the features of the invention are associated. A tank 2 for containing paper making material or stuff receives a supply thereof through an inlet 4. The paper making stuff will as usual include water having in suspension fibers for forming the paper sheets.

A drum 6 of special form is carried by a shaft 8 rotatable in bearings such as 10 at opposite sides of the tank 2 and for rotation at the desired speed the shaft may be driven by a belt engaging a pulley 12 thereon. Of course the shaft and drum may be rotated by any other means desired.

Instead of a paper making drum of usual form we provide a drum made up of a plurality of hollow platens 14 which are supported by pipe supports 16 from a central hub 18. The pipes 16 are in communication with axial passageways 19 through the hub which are open at their outer ends at one side of the hub, as on the left. The open ends of the passageways may be called ports.

A flange 20 abuts the left hand side of the hub and is rotatably adjustable relative to the axis of rotation of the shaft. A depending portion 21 thereof is provided with a slot 22 for a bolt 24 threaded into a disc 26 carried by the left-hand bearing 10.

A chamber 28 circumferentially disposed about the flange 20 has an open side adjacent the end of the hub, so that as the hub rotates the ports or open ends of the passageways 19 register with the chamber and move along the same and then out of registration therewith.

A second chamber 30 is provided at the upper side of the flange and the passageways 19 may register therewith as with chamber 28. By means of a pipe 29 the chamber 28 may be connected to a suction apparatus such as a vacuum pump so that while the drum is in rotation one after the other of the passageways 19 may register with the chamber whereby the platens are successively subjected to the suction action.

The chamber 30 is provided with a pipe 32 which may be connected to air supplying means whereby air delivered to the chamber will be delivered into the platens accordingly as the ports rotate into registration therewith.

The upper open sides of the platens are covered by a structure on which sheets of paper may be formed. Preferably a plate 40 which is perforated as shown is secured to the upper sides of the platens. This plate

⁵ is relatively thin but capable of supporting a lower screen cloth element 42 and an upper paper making screen cloth element 44. The lower element 42 is preferably of coarser mesh than the upper element for the following reasons. The upper relatively fine mesh element is suitable for forming paper, while the lower element is coarser to space the upper element from the plate so that suction is distributed throughout the entire surface of

¹⁵ the upper making element.

The supporting plate is secured in any suitable manner to the platen while the wire cloth elements may be secured thereto by soldering along the marginal edges thereof.

²⁰ As the drum rotates in the direction of the arrow one platen after the other becomes submerged in the paper making material within the tank. As platens becomes sub-

²⁵ merged in the paper making material the passageway in communication with the platens rotates into registration with the suction chamber 28 so that the platen is under the influence of the suction. By this action

³⁰ the fibers of the paper making material are drawn onto the making screen of the platen. Of course various speeds may be employed for the drum so that various amounts of ma-

³⁵ terial may be drawn onto the platen. When the platens rotate out of the paper making material the passageways 19 will rotate in register with the chamber 28 for a time so

⁴⁰ that by the suction the sheet on the face of the platen is freed of water to considerable extent leaving a film of paper making fibers on the platen. As the passageways or ports

⁴⁵ pass out of register with the suction chamber 28 and into register with air chamber 30 air pressure may be delivered to the platen which

⁵⁰ will more or less according to the degree of pressure tend to force the sheet from off the

⁵⁵ making screen of the platen.

An endless apron 50 or belt preferably of felt is provided which may be called a wet

⁶⁰ or lower felt. This is supported and driven by rolls 52, 54, 56, 58 and 60 as shown.

An upper endless apron 51 of felt or the like is supported and driven by rolls 62, 64, 66, 68 and 70, all as shown.

⁶⁵ A suction box 72 having a lower perforated face is disposed over the lower run of the felt 50 and is connected by a pipe 74 to any suitable suction means such as a pump.

A similar suction box 73 having a pipe 74 connected thereto is disposed at the right of

⁷⁰ roll 52.

As the drum rotates and the sheets on the

⁷⁵ platens contact with the wet felt 50 the action of the suction boxes 72 and 73 tends to

⁸⁰ cause the sheets to stick to the felt and be

carried thereby around and upwardly between the rolls 52 and 62 and along between the felts. Air delivered to the platens as the passageways register with chamber 30 tends to cause the sheets on the platens to be blown therefrom so that either by the action of either of the suction or air or both the sheets are caused to adhere to the felt and are thereby removed from the platens.

The rolls 54 and 64, 56 and 66, 58 and 68 ⁷⁵ are arranged to function as squeeze rolls and press the felts together so as to squeeze water from the sheets between the felts.

One end of an apron or felt of a drying apparatus is represented at 80 which is supported by a roll 82. This apron is for receiving sheets delivered thereto by the felts 50 and 51 and will carry the sheets to the apparatus (not shown) for a drying operation.

To insure the transfer of sheets from felts ⁸⁵ 50 and 51 to the apron 80 the following is provided: A suction box 84 having a perforated face is disposed above the lower run of the upper felt. As sheets are carried forwardly by the felts the sheets are urged by ⁹⁰ suction against the upper felt so that they are carried by the upper felt along and over the apron 80. As the sheets pass by the suction box 84 they may drop onto the apron 80 and be carried thereby into the drying ⁹⁵ apparatus.

The box 84 may be connected by a pipe 86 to any suitable form of suction apparatus.

To facilitate the dividing of the sheets longitudinally as they are formed on the ¹⁰⁰ platens a pipe 75 is provided which has a nozzle 77 at the inner end thereof. This or several of them may be arranged so that air or water delivered thereto will be directed onto the sheets on the platens as they are carried therewith. By the action thereof the sheet forming material is removed from the platen in a comparatively narrow strip or strips across the sheet. This divides the sheet and provides uneven tapering deckle ¹⁰⁵ edges.

As another feature of the invention the roll 52 may be hollow and have a perforated surface so that it may be acted upon by suction and cause the sheets to stick to the felt. ¹¹⁰ This is desirable in some cases to co-operate with the suction boxes and introduction of air into the platens to bring about the transfer of sheets from the platens onto the felt.

When it is desired to divide the sheets on the platens transversely or longitudinally into a plurality of smaller size sheets it may be accomplished by closing up the mesh in the making screen as by applying solder thereto as shown at 46 in Fig. 3.

In operation the drum is rotated so as to submerge the platens one after the other in the paper making material in the tank. At the proper time the ports of the passageways rotate into register with the chamber so that ¹²⁵ ¹³⁰

the suction brings about the depositing of fibers on the platens. As the platens rotate out of the paper making material so as to bring the sheets on the faces thereof into engagement with the felt 50 the sheets tend to stick or adhere thereto so that they are removed from the platens and carried between the felts 50 and 51.

The suction box or boxes assists in the removal of the sheets from the platens and when desired air pressure may be supplied to chamber 30 so that as the ports register therewith air is delivered to the underside of the sheets which will tend to force them from the platens onto the felt.

As the sheets are carried forwardly by the felts they are subjected to the action of the squeeze rolls to free them of water in so far as is possible and finally they are delivered onto the apron 80 of the drying apparatus. In order that the sheets will be carried by the upper felt across the gap between the lower felt and apron they are suctionally pulled against the upper felt by the suction box 84.

The drum formed by separate platens each of which is capable of forming separate sheets facilitates the production of separate and unjoined sheets. All edges of each of the sheets are of tapering thickness and more or less uneven to give the deckle effect desired and by continuous rotation of the drum the successive sheets are formed and delivered one after the other to the continuously moving felts. In this way it is possible to obtain the production equal to that of continuous web making apparatus, while the sheets produced are equal to those made by the prior art hand method.

Various changes may be made in the form of the apparatus without departing from the spirit and scope of the invention and therefore we prefer to be limited by the appended claims rather than by the foregoing description.

What we claim is:

1. In an apparatus for making separate sheets of deckle edge paper comprising, a drum having separate platens carried by a central rotatable hub, the said hub and platens having intercommunicating passageways and a flange non-rotatable relative to said hub having a chamber with which the passageways of the hub may register.

2. In an apparatus for making separate sheets of deckle edge paper comprising, a drum having separate platens removably carried by a central rotatable hub, a flange non-rotatable at one end of said hub provided with a chamber open at a side adjacent said hub, the said hub and platens having intercommunicating passageways which may register with said chamber as the hub rotates.

3. In an apparatus for making separate sheets of deckle edge paper comprising, a

central rotatable hub, a plurality of hollow platens disposed radially of said hub having curved surfaces which form the periphery of a drum, the surfaces comprising paper making screen cloth.

4. In an apparatus for making separate sheets of deckle edge paper comprising, a central rotatable hub, a plurality of hollow platens disposed radially of said hub having curved surfaces which form the periphery of a drum, the surfaces comprising paper making screen cloth, a non-rotatable flange at one end of said drum having a suction chamber and the hub provided with passageways in communication with the platens and adapted for registration with the chamber of the flange as the hub rotates.

5. In an apparatus for making separate sheets of deckle edge paper comprising, a rotatable hub, hollow supports extending radially thereof, hollow platens on said supports, the outer surfaces of said platens being curved concentrically relative to the axis of rotation of said hub and formed of wire screen cloth.

6. In an apparatus for making separate sheets of deckle edge paper comprising, a rotatable hub provided with axial passageways opening at one end thereof, a non-rotatable flange at said end of the hub provided with separate suction and air chambers having an open side adjacent said hub, hollow supports extending radially of said hub, the said hub provided with passageways connecting said hollow supports and first-named passageways and hollow platens carried by said supports in communication with said passageways and having curved paper forming surfaces to provide a cylindrical surface concentric with the axis of rotation of the hub.

7. In an apparatus for making separate sheets of deckle edge paper comprising, a drum including separate platens having curved surfaces which are concentric with respect to the axis of rotation of the drum, an endless lower felt supported by a plurality of rolls so that a lower run thereof contacts with the curved surfaces of the platens as they are rotated by the hub, an endless upper felt supported by a plurality of rolls so that a lower run thereof co-operates with the upper run of the lower felt for receiving sheets from the platens therebetween.

8. In an apparatus for making separate sheets of deckle edge paper comprising, a drum including separate platens having curved surfaces which are concentric with respect to the axis of rotation of the drum, an endless lower felt supported by a plurality of rolls so that a lower run thereof contacts with the curved surfaces of the platens as they are rotated by the hub, an endless upper felt supported by a plurality of rolls so that a lower run thereof co-operates

- with the upper run of the lower felt for receiving sheets from the platen therebetween and a suction box over the lower run of the lower felt disposed to act on sheets on the platens to draw them towards said lower felt.
9. In an apparatus for making separate sheets of deckle edge paper comprising, a drum including separate sheet forming platens, a lower endless felt supported by a plurality of rolls so that its lower run contacts with outer paper forming surfaces of said platens, an upper endless felt supported by a plurality of rolls with its lower run in contact with the upper run of said lower felt and extending beyond the said lower run, a third felt below the lower run of the upper felt and adjacent the lower felt and a suction box over the lower run of the upper felt extending beyond adjacent ends of said lower and third felt.
10. In an apparatus for making separate sheets of deckle edge paper comprising, a drum including separate platens having concentrically disposed sheet forming surfaces, a suction box above said drum having a suction side conforming to the contour of the surfaces of the platens, a lower endless felt supported by a plurality of rolls having its lower run extending between said suction box and said drum, an upper endless felt supported by a plurality of rolls having its lower run in contact with the upper run of the lower felt and at a point away from said drum extending beyond the upper run of the lower felt, a drier felt having a receiving end disposed below the extending part of the upper felt and adjacent the lower felt and a suction box above the lower run of the upper felt overlapping adjacent portions of the lower and drier felt.
11. In an apparatus for making separate sheets of deckle edge paper comprising, a platen having an open upper side, a paper forming surface thereover including a plurality of superposed members having openings of different areas therethrough.
12. In an apparatus for making separate sheets of deckle edge paper comprising, a platen having end and side walls, a perforated plate removably affixed to the upper sides of the walls and a plurality of superposed screen cloth members of different mesh over the perforations of said plate.
13. In an apparatus for making separate sheets of deckle edge paper comprising, a rotatable drum having separate platens provided with paper forming peripheral surfaces, a roll thereabove, a felt movable between said roll and surfaces, the said roll being hollow and having a perforated wall and a suction box having a perforated side against said belt adjacent said roll.
14. In an apparatus for making separate sheets of deckle edge paper comprising, a rotatable drum having separate platens provided with paper making surfaces, a suction roll thereabove, a felt movable between said roll and surfaces of said platens, and a suction box adjacent said roll having a perforated face disposed above said felt.
15. In paper making apparatus comprising in combination, a drum including separate platens having perforated paper forming surfaces and means associated with the surface of at least one platen closing the perforations of the surface thereof along an irregular strip to form separate paper forming surfaces.
16. In apparatus for making paper, comprising in combination, a rotatable drum including a plurality of separate platens each having curved paper making surfaces and an endless lower felt supported by a plurality of rolls so that a lower run contacts with the curved surfaces of the platens, one of said rolls being located at a side of said drum for guiding said felt into contact with said drum.
17. In apparatus for making paper comprising in combination, a rotatable drum including a plurality of separate platens each having curved paper making surfaces and an endless lower felt supported by a plurality of rolls so that a lower run contacts with the curved surfaces of the platens, one of said rolls being located at a side of said drum for guiding said felt into contact with said drum, and a nozzle adjacent the drum for directing a fluid onto the surface of said drum.
18. In an apparatus for making paper comprising in combination, a rotatable drum including separate platens having curved surfaces, upper and lower endless felts supported by rolls so that a lower run of the lower felt contacts with the surfaces of the platens and the upper and lower runs of the lower and upper felts are superposed to receive therebetween sheets from said platens and a pair of press rolls acting on said superposed runs.
19. In apparatus for making paper comprising in combination, a rotatable drum including separate paper forming platens, an endless felt supported by rolls so that a part thereof contacts with the surface of said platens and a run thereof extends away from said drum, a part of another felt adjacent the end of said run and a suction box above said end of the run and said part of said other felt.
20. In apparatus for making paper comprising in combination, a rotatable drum having paper making surfaces, a lower endless felt supported by a plurality of rolls so that a lower run thereof contacts with the surface of the drum, an upper endless felt supported by a plurality of rolls with its lower run in contact with the upper run of the lower felt, a part of a third felt adjacent the upper run of the lower felt and a suction box above ad-

jacent portions of said lower felt and said part of the third felt.

21. In apparatus for making paper comprising in combination, a rotatable drum including a plurality of separate platens each having curved paper making surfaces and an endless felt supported so that a lower run thereof contacts with the curved surfaces of the platens, and another felt having a portion disposed in superposed relation on the first-named felt whereby paper formed on the platen will be received by and between the superposed portion of the felt.

10 In testimony whereof we affix our signatures.
